UNITED STATES PATENT OFFICE.

WILLIAM MCCLAVE, OF SCRANTON, PENNSYLVANIA, ASSIGNOR TO MCCLAVE-BROOKS COMPANY, OF SCRANTON, PENNSYLVANIA, A CORPORATION OF PENNSYLVANIA.

STOKING MECHANISM FOR FURNACES.

SPECIFICATION forming part of Letters Patent No. 705,599, dated July 29, 1902.

Application filed December 28, 1901. Serial No. 87,615. (No model.)

To all whom it may concern:

Be it known that I, WILLIAM MCCLAVE, a citizen of the United States, residing at Scranton, in the county of Lackawanna and State of Pennsylvania, have invented certain new and useful Improvements in Stoking Mechanism for Furnaces; and I do hereby declare the following to be a full, clear, and exact description of the invention, such as will enable others skilled in the art to which it appertains to make and use the same.

My invention relates to stoking mechanism for furnaces, and has particular relation to means for feeding fuel from a fuel-hopper to the upper end of an inclined grate in a furnace.

It consists in a stoking means comprising a reciprocating pusher, a rocking member outside the furnace-front for actuating the same, the said rocking member being journaled upon a power-shaft, and means for regulating the amount of motion imparted from the power-shaft to the said rocking member whereby the throw of the reciprocating pusher is altered.

It further consists in certain other novel constructions, combinations, and arrangements of parts, as will be hereinafter fully described and claimed.

In the accompanying drawings, Figure 1 represents a vertical transverse section through a stoking-hopper for a furnace, showing a reciprocating pusher adapted to work in the lower end thereof and means outside the furnace-front for operating the same. Fig. 2 is a front elevation of a portion of a furnace, showing fuel-hoppers mounted thereon and pusher-operating mechanism arranged upon a front rock-shaft. Fig. 3 represents a detail view, partially in section and partially in elevation, of the rocking actuating member for the hopper-pusher. Fig. 4 is a detail sectional view showing the means for varying the throw of said rocking member. Fig. 5 is a top plan view of a connecting member for operating two pushers simultaneously. Fig. 6 is a front elevation of the same applied to a power-shaft. Fig. 7 is a transverse section through the connecting member, showing the journal for engaging the pitman of the hopper-pusher.

In supplying fuel to the grate of a furnace

by a forced feed it is usual to employ a reciprocating slide or pusher in the lower portion of the hopper, which as it moves back and forth will push given quantities of fuel out upon the grate in the furnace.

I have illustrated such a mechanism in the drawings, in which—

1 is a hopper for a furnace, adapted to receive the fuel which is to be fed upon the grate.

2 represents a reciprocating pusher mounted in the bottom of the hopper and moving back and forth over the dead-plate 3 of the furnace. This pusher 2 consists of a comparatively long webbed bar extending from one end of the hopper to the other and connected by suitable mechanism with a rocking power-shaft 4, mounted outside the front 5 of the furnace. It is preferable to connect 70 the operating means with a long pusher of this character at at least two places, so that exactly the same amount of movement will be imparted to one end of the said pusher that is given to the other. By this means 75 there will be no twisting or uneven movement given to the said pusher. The pusher 2 may be made of sufficient length to extend entirely across the front of the furnace; but in furnaces of the size usually employed with 80 mechanical stokers it is preferable to employ two hoppers, as shown in Fig. 2 of the drawings, and employ a separate pusher for each hopper.

Mounted upon the rock-shaft 4 in front of each hopper is a rocking member 6, which is loosely journaled on said rock-shaft, being formed with an elongated sleeve 7, having bearings 8 at its ends, so that the said sleeve only engages the shaft 4 at its ends and not 90 for its entire length. The sleeve 7 is formed with outwardly-extending arms 9 at each end, which extend at their outer ends parallel with the shaft 4 and are formed with enlargements 10, into which are screwed wrist or journal 95 pins 11. These wrist-pins 11 are preferably in the form of headed bolts screwed into the ends of the arms 9, as illustrated in Fig. 3. Each of these wrist-pins 11 is connected by means of a pitman 12 with the pusher 2, the inner end of the pitman engaging a pair of perforated lugs 13. Each outer end of the pitman is formed with an eye 14, loosely engaging the wrist-pins 11. The wrist-pins 11

are made of sufficient length so that the sleeve 7 may be moved longitudinally upon the shaft 4 without moving the pitmen 12 to one side or the other. In order to guard against such movement of the pitmen 12, I preferably place brackets 15 upon the furnace-front 5, providing the said brackets with slots or apertures 16, through which the said pitmen 12 may move as they are reciprocated in actuating the pusher 2. The said pitmen 12 are thus positively guided in their reciprocating movement by the brackets 15 and will not be influenced by the longitudinal movement of the sleeve 7 and the wrist-pins 11, carried thereby, when the said sleeve is moved longitudinally on the shaft. The movement of the shaft 4 is imparted to the sleeve 7 to a greater or less extent by means of a collar 17, secured to said shaft 4 and provided with a laterally-projecting lug 18, which is arranged to extend into a correspondingly-shaped recess or notch 19 in one end of the sleeve 7. The lug 18 is tapered at its sides and engages a correspondingly-tapered face in the notch 19, as clearly illustrated in Fig. 4. The amount of movement imparted to the sleeve 7 from the collar 17 is regulated by the extent to which the lug 18 projects into the said notch 19. If the sleeve 7 is held upon the shaft 4, so that the notch 19 only engages the lug 18 near its point or outer end, the said sleeve will only receive a comparatively small amount of movement from the shaft, since the shaft can move quite a distance before the lug 18 will engage the opposing face of the notch 19. If, however, the sleeve 7 is forced closer to the collar 17, there will be less play between the lug and the recess or notch 19, and the sleeve will be forced to turn to a greater extent. When the sleeve 7 is forced snugly against the collar 17, the lug 18 will be brought into a tight engagement with the notch or recess 19, and the sleeve 7 will then receive the full amount of movement which is given to the shaft 4. The position of the sleeve 7 with respect to the collar 17 is controlled by means of an adjusting-nut 20, which is arranged to bear against the opposite end of the sleeve from the collar 17. This nut 20 engages the screw-threads 21 of a sleeve 22, which is keyed or otherwise firmly fixed in position upon the shaft 4 after the sleeve 7 has been slipped upon the same. The nut 20 is preferably formed with a projecting flange 23, forming a hand-engaging portion which may be milled or otherwise roughened, so as to be easily grasped and turned. A jam or lock nut 24 also engages the threads of the sleeve 22, and after the nut 20 has been adjusted to give the proper play to the sleeve 7 the said nut 24 is screwed tightly against the nut 20, so as to lock the same in its adjusted position. It will be evident that the throw of the arms 9, carried by the sleeve 7, can be easily and accurately adjusted by means of the nuts 20 and 24 to vary the throw given to the pusher 2 in the hopper. Where there are

two hoppers upon the furnace, as illustrated in Fig. 2, the mechanism for operating the two pushers, one in each hopper, is preferably complete upon each side of the machine, there being separate sleeves 7 7 for each pusher and separate adjusting means and operating-collars 17 for each. By this structure one side of the furnace may be arranged to have fuel fed to it more rapidly or less rapidly than the other side. It is sometimes desirable, however, to operate both of the pushers from one lugged collar 17, in which case I connect the sleeves 7 7, as illustrated in Figs. 5 and 6, by means of a bar 25, which may be formed integral with both of said sleeves or may be secured to the ends of each. This bar 25 bridges the space between the two sleeves, and in order to facilitate its connection with the pitmen of the pushers is formed with journals 26 26, which are arranged in the same position which would have been occupied by the wrist-pins 11 had the two sleeves remained disconnected. A curved slot 27 through the connecting-bar 25 at each journal 26 accommodates the engagement of the said journals by the pitmen. By this structure the bar 25 is not appreciably weakened at the point of its engagement with the pitmen, since the journals 26 complete the line of metal along the inner side of the bar 25 and strengthen the same at these points. The bar 25 is preferably of a flattened elliptical or oval shape in cross-section, as shown in Fig. 7, so that a very stiff bar is formed without a great bulk of metal. In this structure only one lugged collar 17 is needed, as shown in Fig. 6. This collar engages the notch, as above described, in one of the sleeves 7, and the motion therefrom is communicated through the bar 25 to the other sleeve 7, so that no lugged collar or binding-nuts are employed in connection with said latter sleeve. Of course it will be understood that the rock-shaft 4 receives its rocking movement from any suitable source of power. (Not shown.)

The pusher 2 preferably slides back and forth upon the dead-plate 3, having a frictional contact therewith at one point—say at the outer edge thereof—as at 28, while the inner edge of the pusher 2, which engages the fuel and receives its weight when it is thrust inwardly, is preferably mounted upon anti-friction-wheels 29, so as to facilitate its operation. It will be evident that I may connect the pusher with the sleeve 7 at more than two points, if desired, without departing in the least from the spirit of the invention. It will be seen that the throw of the pusher 2 can be altered without stopping the movement of the rock-shaft 4, it being easy to manipulate the nuts 20 and 24 upon a rock-shaft of this character.

Of course it will be evident that the lug 18 may be formed upon or secured to the shaft 4 in any suitable manner aside from the collar 17, heretofore described, and I do not wish

to be understood as limiting my invention to the use of such a collar.

From the above description it will be evident that the pushers may be operated at 5 different speeds and have different amounts of throw with respect to the actuating rock-shaft 4 as found desirable, the mechanism used for producing such a result being extremely easy of manipulation and yet positive in its action.

Having now described my invention, what I claim as new, and desire to secure by Letters Patent, is—

1. A stoking mechanism, comprising a rock-shaft, a pusher operating in the fuel-hopper, means for reciprocating the same, comprising a rocking sleeve on said shaft, means projecting from the rock-shaft and directly engaging the rocking sleeve, and means for adjusting the rocking sleeve with respect to the said projection for altering the throw of said sleeve and thereby the extent of the movement of the pusher, substantially as described.

2. A stoking mechanism for furnaces, comprising a reciprocating pusher adapted to feed fuel upon a grate, a power-shaft, an actuating projection thereon, a rocking sleeve journaled on said shaft and connected with the said pusher, means upon the said shaft for adjusting the sleeve with respect to the said projection for varying the amount of movement imparted by the rock-shaft to the said rocking sleeve, substantially as described.

3. A stoking mechanism, comprising a reciprocating pusher operating in connection with a fuel-hopper, a rock-shaft, and a rocking member, comprising a sleeve journaled on said shaft, pitmen connecting said sleeve with the pusher, and longitudinally-adjustable means on the rock-shaft for varying the amount of movement imparted to said sleeve and thereby the throw of the pusher, substantially as described.

4. A stoking mechanism, comprising a pusher operating in connection with a fuel-hopper, a rock-shaft for imparting movement thereto, a rocking member journaled upon the said rock-shaft, comprising a sleeve having arms projecting therefrom, wrist-pins carried by the said arms, pitmen connecting the wrist-pins with the pusher, and means adjustable longitudinally of the rock-shaft for altering the amount of movement received by the sleeve from the rock-shaft in accordance with the extent to which it is desired to operate the pusher, substantially as described.

5. A stoking mechanism, comprising a pusher operating in connection with a fuel-hopper, a rock-shaft for actuating the same, 60 a rocking sleeve provided with a recess and adjustable longitudinally on said shaft and having end bearings journaled thereon, arms springing from said sleeve and extending parallel with the rock-shaft, wrist-pins carried by the ends of said arms and having comparatively long bearings formed thereon, pitmen connecting the said wrist-pins with

the said pusher at a plurality of points, a collar upon the rock-shaft having a lug adapted to engage a recess formed in said sleeve, and means limiting the longitudinal movement of the sleeve on the rock-shaft for regulating the extent to which said recessed sleeve engages said lug for controlling the extent of the reciprocation of the said pusher, substantially as described.

6. A stoking means, comprising a fuel-feeding pusher, a rock-shaft for actuating the same, adjusting mechanism interposed between the rock-shaft and the pusher, comprising a sleeve journaled on the rock-shaft, pitmen connecting the sleeve with the pusher, a lug carried by the said rock-shaft having a tapering contour, the said sleeve having a recess of correspondingly-tapering shape, and adjusting-nuts for holding the sleeve in engagement with the said lug, the movement received by the said sleeve corresponding to the extent to which the same is forced against the said lug, substantially as described.

7. A stoking means, comprising a reciprocating pusher operating in a fuel-supply mechanism, a rock-shaft, a sleeve journaled upon and capable of moving longitudinally thereon, pitmen connected at one end with the pusher and at their outer ends with the rocking sleeve, brackets on the furnace-front for holding the pitmen in position, and means for limiting the longitudinal movement of the sleeve on the rock-shaft to regulate the movement of the pusher, the said brackets preventing the pitmen from being moved sidewise out of proper alinement when the sleeve is adjusted, substantially as described.

8. A stoking mechanism, comprising fuel-feed pushers, a rock-shaft for moving the same, sleeves journaled upon the rock-shaft opposite each pusher, means connecting the sleeves and the pushers, means for connecting the sleeves so that they will operate simultaneously, and means for limiting the longitudinal movement of one of the sleeves upon the rock-shaft with the same or a less movement than the movement of the rock-shaft, for operating both sleeves and varying the throw of the pusher, substantially as described.

9. A stoking mechanism, comprising stoking-pushers, a rock-shaft for moving them, sleeves, journaled on the rock-shaft opposite each pusher, means connecting the said sleeves, journals formed in the metal in said connecting means, pitmen engaging said journals and connecting them with the pushers, and means for actuating one of the sleeves from the rock-shaft, so that both will be operated to move the pushers, substantially as described.

In testimony whereof I hereunto affix my signature in presence of two witnesses.

WILLIAM MCCLAVE.
